UNITED STATES PATENT OFFICE.

EDWIN O. TOWNSEND, OF NEW YORK, N. Y.

DESIGN FOR A MONUMENT.

SPECIFICATION forming part of Design No. 29,862, dated December 20, 1898.

Application filed November 23, 1898. Serial No. 697,292. Term of patent 7 years.

To all whom it may concern:

Be it known that I, EDWIN O. TOWNSEND, a citizen of the United States, residing at the city of New York, borough of Manhattan, in the county and State of New York, have invented and produced a new and original Design for a Monument, of which the following is a specification, reference being had to the accompanying drawing, forming a part thereof, which represents a perspective view of a monument embodying the features of my design.

The leading feature of the design consists in a body made in the semblance of a sarcophagus, a subbase for the sarcophagus, and a plinth for the subbase, the subbase being ornamented with molding and with plain and rough panels, and the plinth being provided with rough panels separated by plain surfaces.

In the detail of the design the sarcophagus constituting the main feature of the body is tapering and is provided with ornamental legs, its ends being decorated with rough panels and its front being decorated with garlands of leaves and with ornamental and bead-like figures. The cap portion of the body, constituting the cover of the sarcophagus, is decorated with ogee molding and in-lined molding in pyramidal order. 25 30

I claim—

The design for a monument herein shown and described.

EDWIN O. TOWNSEND.
